UNITED STATES PATENT OFFICE.

ANDERS H. NESHEIM, OF MILWAUKEE, WISCONSIN, ASSIGNOR TO FEDERAL STEEL SASH COMPANY, OF WAUKESHA, WISCONSIN, A CORPORATION OF WISCONSIN.

METAL WINDOW.

Application filed March 10, 1924. Serial No. 698,140.

To all whom it may concern:

Be it known that I, ANDERS H. NESHEIM, a citizen of the United States, and resident of Milwaukee, in the county of Milwaukee, and State of Wisconsin, have invented new and useful Improvements in Metal Windows, of which the following is a description, reference being had to the accompanying drawings, which are a part of this specification.

10 This invention relates to improvements in metal windows of the pivotal type.

One of the objects of the present invention is to provide a metal window in which the frame and sash are formed of commercial 15 or stock metal bars of the desired cross sectional shape welded together.

A further object of the invention is to provide a metal window having a medial section pivotally connected to the main portion in a very simple manner.

20 A further object of the invention is to provide a metal window having a pivoted sash portion which may be easily removed from the sash frame without the use of 25 tools.

A further object of the invention is to provide a metal window in which all of the joints of the pivotal sash are overlapped at two places to form a weatherproof construction.

30 A further object of the invention is to provide a metal window which is of simple construction, is strong and durable and is well adapted for the purpose described.

35 With the above and other objects in view, the invention consists of the improved metal window and its parts and combinations as set forth in the claims, and all equivalents thereof.

40 In the accompanying drawing in which the same reference characters indicate the same parts in all of the views:

Fig. 1 is a side view of the outer side of the improved metal window;

45 Fig. 2 is a vertical sectional view thereof taken on a larger scale on line 2—2 of Fig. 1;

Fig. 3 is a horizontal sectional detail view taken on line 3—3 of Fig. 1;

50 Fig. 4 is a horizontal sectional detail view taken on line 4—4 of Fig. 1; and

Fig. 5 is a detail sectional view of the pivotal connection.

Referring to the drawing, the numeral 8 55 indicates a rectangular sash frame formed

of bars of metal connected together in a manner to provide glazing openings 9 and a central sash opening 10 for pivotally receiving a sash 11. The top, bottom and opposite side portions of the sash frame indicated respectively by the numerals 12, 13 and 14, are preferably formed of commercial steel of T-shape in cross section and the inner edge portions of said side portions are provided with notches 15 to receive the outer 60 side flanges 16 of the sash 11. The sash is also formed of commercial steel of T-shape in cross section with the flat sides of the T extending outwardly and the parts welded together to form a rectangularly shaped 70 rigid sash. The upper half portion of the sash including the side flanges 16, is offset inwardly as indicated by the numeral 17 to position said upper half of the sash on the inner side of the flanges of the sides 14 and 75 the top 12, and position the lower half of the sash on the outer sides of the flanges of the sides 14 and the bottom portion 13 of said sash frame as clearly shown in all of the figures of the drawing. The medial portions 80 17 of the sash which are bent to offset the upper part of the sash are in horizontal alinement with the notches 15 and the outer opposite edge bent portions extend through said notches as shown to provide an overlapping 85 of the parts and to permit the lower half of the sash to swing outwardly and the upper half inwardly in swinging the sash to open position.

The lower half portions of the side members 14 and the lower member 13 have angle members 18 and 19 connected thereto by welding and the upper notched end portions 18' of the angle members 18 form fulcrums for supporting the sash and upon which the 90 sash swings. Said angle members 18 and 19 are engaged by the inner edges of the T-shaped members of the lower half portion of the sash in overlapping relation to form a second overlapped joint for the lower portion 100 of the sash.

The inner edge portions of the T-shaped members of the upper portion of the sash are also offset inwardly to correspond with the outer faces of said portions and at the 105 points of offset of the side members, horizontal shoulders 20 are formed which bear upon the notched ends 18' before mentioned.

The upper half portion of the sash on the outer sides and on top of the stem por- 110

tions of the T-shaped parts, has mounted thereon angled members 21 and 22 which extend outwardly therefrom and overlap the inner edges of the frame members 12 and 14 to form the second sealing means between the upper half portion of the sash and the frame opening. As thus formed there is a double overlapping between the edges of the sash and the sash frame to form a weather-
10 proof sealing means therebetween.

The lower ends of the angled members 22 have notched portions 23 which also bear upon the upper notched end portions 18' of the angled members 18, and in addition the 15 shouldered portions 20 also swing on said portions 18'.

As thus constructed the sash is medially pivotally supported on the upper ends of the angled members with the outer lower half 20 portion of the sash extending outside of the sash frame, and the inner upper half portion of the sash extending on the inner side of the sash frame, as clearly shown in Fig. 2. Both of these half portions are offset with 25 relation to the sash frame to provide the double overlapping of the parts and which parts serve as stops to limit the closing movement of the sash. This offset relation also provides for the pivotal engagement of the 30 shoulders 20 and 23 with the angle members 18. When the sash is in open position, it may be withdrawn inwardly and removed from the frame without the use of tools.

From the foregoing description it will be 35 seen that the metal window may be made from commercial strips of metal and without the use of hinges or trunnions in a very simple manner.

What I claim as my invention is:

40 1. A metal window, comprising a sash frame having opposite side members formed with notches and also having angled portions provided with inner upper fulcrum ends, and a sash having offset side flanges 45 which extend through the notches, said flanges also having shouldered portions which rest upon the fulcrum ends to pivotally connect the sash thereto, the lower portions of the side flanges and a lower 50 flange of the sash overlapping the lower side and bottom portion of the sash frame opening, the upper portions of the side members and an upper flange of the sash being overlapped by the upper portions of the side 55 members of the frame and an upper flange of said frame.

2. A metal window, comprising a sash frame formed of commercial lengths of angular metal and having opposite side flanges 60 provided with notches, said frame also having angled portions on the inner bottom and lower half side portions of the frame which terminate medially of the height of the frame opening and form fulcrum end portions, a sash also formed of commercial 65 lengths of angular metal and having front, upper and lower and opposite side flanges, the upper portions of the flanges being offset from the lower portions and the offset parts of the side flanges extending through the notches of the sash frame side flanges to 70 position the lower portions of the sash flanges outside of the frame and the upper portions inside of the frame, said sash also having inner opposite side shoulders which 75 bear upon the fulcrum end portions of the frame to pivot the sash thereon.

3. A metal window, comprising a sash frame formed of lengths of commercial metal of T-shape in cross section with their flanged faces extending outwardly and their 80 stem portions inwardly, the opposite side flanges being notched, said frame also having angular bottom and side members, the side members terminating medially of the 85 height of the sash opening to form fulcrum ends, and a sash also formed of lengths of commercial metal of T-shape in cross section with their flange faces extending outwardly and their stem portions inwardly, the said sash lengths medially of their height 90 being offset inwardly and said offset portions extending upwardly to the upper portions of the sash, the side edges of the offset portions extending through the notches of 95 the sash frame to position the lower portions of the sash flanges outside of the frame and the upper portions inside of the said frame, the inner edge offset portions of said sash stems forming shoulders which engage the 100 fulcrum ends of the frame to pivot the sash thereon.

4. A metal window, comprising a sash frame formed of commercial lengths of angular metal and having opposite side flanges 105 provided with notches, said frame also having angled portions on the inner bottom and lower half side portions of the frame which terminate medially of the height of the frame opening and form fulcrum end portions, a sash also formed of commercial 110 lengths of angular metal and having front, upper and lower and opposite side flanges, the upper portions of the flanges being offset from the lower portions and the offset parts of the side flanges extending through the notches of the sash frame side flanges outside of the frame and the upper portions inside of the frame, the side portions of said sash 115 also having shoulders which bear upon the fulcrum end portions of the frame to pivot the sash thereon, and angle members mounted on the inner upper and opposite sides of the sash and coacting with the frame in forming a double overlapping of the parts 120 between the upper portion of the sash and the upper portion of the frame, said sash angle members at their lower ends also bearing on the fulcrum end portions of the frame, the angled portions of the frame also 125 130

coacting with the lower portions of the sash to form a double overlapping between the lower portions of the frame and sash.

5. A metal window, comprising a sash frame formed of lengths of commercial metal of T-shape in cross section with their flanged faces extending outwardly and their stem portions inwardly, the opposite side flanges being notched, said frame also having angular bottom and side members with the side members terminating medially of the height of the sash opening to form fulcrum ends, and a sash also formed of lengths of commercial metal of T-shape in cross section with their flange faces extending outwardly and their stem portions inwardly, the said sash lengths medially of their height being offset inwardly and said offset portions extending upwardly to the upper portion of the sash, the side edge of the offset portions extending through the notches of the sash frame to position the lower portions

of the sash flanges outside of the frame and the upper portions inside of the said frame, the inner edge offset portions of said sash stems forming shoulders which engage the fulcrum ends of the frame to pivot the sash thereon, angle members mounted on the stem portions of the upper half section of the sash and at their lower ends bearing on the fulcrum ends of the frame angle members, said sash angle members coacting with the upper half portions of the frame in forming a double overlapping between the upper portions of the sash and the frame, said frame angle members also coacting with the stem portions of the lower half portions of the sash in forming a double overlapping of the parts between said lower half sash section and the lower portion of the frame. 25 30 35 40

In testimony whereof I affix my signature.

ANDERS H. NESHEIM.
